US0D1084532S

(12) **United States Design Patent** (10) **Patent No.:** **US D1,084,532 S**
(45) **Date of Patent:** **** Jul. 15, 2025**

(54) **PET FEEDER**

(71) Applicant: **Shenzhen Libro Technology Co., Ltd.**,
Shenzhen (CN)

(72) Inventor: **Tianyu Xiao**, Shenzhen (CN)

(73) Assignee: **Shenzhen Libro Technology Co., Ltd.**,
Shenzhen (CN)

(**) Term: **15 Years**

(21) Appl. No.: **29/931,028**

(22) Filed: **Mar. 5, 2024**

(30) **Foreign Application Priority Data**

Sep. 6, 2023 (CN) 202330578712.1

(51) **LOC (15) Cl.** **30-07**

(52) **U.S. Cl.**

(74) Attorney, Agent, or Firm — Andrew C. Cheng

(57) **CLAIM**

The ornamental design for a pet feeder as shown and described.

DESCRIPTION

FIG. 1 is a top, front, left perspective view of a pet feeder of my new design;

FIG. 2 is a bottom, back, right side perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The broken lines in the drawings depict portions of the pet feeder that form no part of the claimed design.

1 Claim, 8 Drawing Sheets
